UNITED STATES PATENT OFFICE.

CHESTER W. METZGAR, OF EASTON, PENNSYLVANIA, ASSIGNOR TO INGERSOLL-RAND COMPANY, OF JERSEY CITY, NEW JERSEY, A CORPORATION OF NEW JERSEY.

COMPRESSOR UNLOADER.

Application filed November 3, 1925. Serial No. 66,494.

This invention relates to compressors, but more particularly to compressor unloaders and the objects of the invention are to secure means for effecting step by step unloading through the agency of a plurality of clearance chambers controlled by a single clearance valve in a simple, cheap and efficient manner.

Another object of the invention is to provide fluid pressure controlled means for limiting the movement of the clearance valve for effecting step by step regulation. Both the clearance valve and the stop are preferably automatically responsive to receive pressure.

Further objects of the invention will hereinafter appear and the invention is shown in one of its preferred forms in the accompanying drawing which is a diagrammatic sectional elevation partly in longitudinal section and partly broken away showing the invention.

Referring to the drawing, the cylinder A shown as double acting is provided with the piston B driven from any suitable engine or motor. The cylinder is provided with suitable intake and discharge valves C and D which may be of the plate type and the air or fluid to be compressed entering at the inlet E is discharged at the outlet F connected as by means of the usual discharge connection or pipe G to the receiver H.

The cylinder is provided with a plurality of sets of clearance chambers J, K and L, O, in this instance two sets of two clearance chambers each being provided, and a single clearance valve P or Q is provided for controlling each set of clearance chambers. There may be as many clearance chambers in each set as desired, but only two being illustrated in the drawing.

The chambers J and K controlled by the valve P are adapted to be placed in successive communication with one end of the cylinder through the ports R and S and the port T while the clearance chambers L and O are adapted to be placed in communication successively with the other end of the cylinder through the ports U and V and the port W. These sets of ports being respectively controlled by the clearance valves P and Q.

Each clearance valve is provided with a plunger X in the cylinder a and a compression spring b underneath the plunger tends to open the valve. Receiver pressure supplied through the pipes c or d holds the clearance valves closed, the supply and release of receiver pressure being controlled by the regulator Y. A second cylinder e for each clearance valve contains a plunger f having a stop pin g projecting into the cylinder a for limiting the movement of the clearance valve according to the position of the plunger f. A spring h beneath the plunger f tends to move the stop pin g outwardly and receiver pressure is admitted to the plungers f for forcing the stop inwardly. The pipes j and k connect the stop cylinders e with the regulator Y as the receiver pressure increases through predetermined degrees. The apparatus and the regulator are so constructed that the clearance valve P is first permitted by the stop g to move a sufficient distance to open the port R of the clearance chamber J as indicated in the drawings for the first step of unloading, and upon a further increase of receiver pressure for the next step of unloading the other valve Q is permitted by its stop g to move a sufficient distance to place the clearance chamber L in communication with the cylinder through the port U. At the next step of unloading, pressure against the plunger f, controlling the stop for the clearance valve P, is released permitting the spring to retract the stop so that the clearance valve P opens the port S and places the clearance chamber K in communication with the cylinder, and for the last step of unloading, a similar operation is carried out for the clearance valve Q which opens the port V and places the clearance chamber O in communication with the cylinder so that the cylinder is completely unloaded.

Any suitable regulator Y may be provided, in this instance the regulator casing Z having a valve chamber o for the auxiliary or pilot valve p having the heads q and r. Receiver pressure is supplied from the receiver H through the pipe s to the port t in the regulator casing so that the space between the valve heads q and r is constantly open to receiver pressure. One end u of the valve chamber o is open to atmosphere, and ports and passages lead from the valve

chamber σ to the valve chambers v of the main operating valves w having the heads x and y . There are four of these main operating valves w all constructed in the same manner and operating in the same manner, but only two of these valves and a portion of the third valve are shown. The two lower valves w shown in the drawing, control the pipes c and d leading respectively to the cylinders for the plungers X of the clearance valves P and Q while the two upper main operating valves w of the regulator control the pipes j and k leading respectively to the cylinders of the plungers f of the stops for the clearance valves P and Q respectively.

The valve chambers v between the valve heads x and y are constantly subject to receiver pressure through the ports 3 connected by passages 4 to the main receiver pipe s and the valves w are provided with shoes 5 controlling ports 6 and 7 for supplying pressure to or releasing pressure from the clearance valve pipes c , d , j and k respectively. The main valves w are actuated by the alternate supply and release of receiver pressure operating on the heads x and y .

The regulator Y is provided with a diaphragm 8 for a diaphragm chamber 9 to which chamber is connected the pipe 10 leading to the receiver. A pin 12 in the guide 13 which bears on the diaphragm, supports the weighted lever 14 pivoted at the point 15 to a bracket 16 on the regulator casing. The pilot valve p is hung by the valve stem 17 from the lever 14 and the valve p is normally at its lowermost position in the valve chest σ so that receiver pressure passes to the four passages 18, 19, 20 and 21 leading respectively to the left hand ends of the operating valves w so that these valves would normally be in their right hand positions as the figure is viewed. Four similar passages of which only two, 22 and 23, are shown connect the right hand ends of the main operating valves w with points in the pilot valve chest σ and these passages are normally open to atmosphere through the open upper end 24 of the valve chest σ .

In the operation of the device, let it be assumed that the receiver pressure has increased sufficiently to actuate the weighted lever 14 sufficiently to lift the pilot valve p to the position shown in the drawing, in which case one operating valve w will be actuated to the left and the pipe c from the casing of the clearance valve P will be placed in communication with atmosphere through the ports 6 and 7 and the atmospheric port 25 in the regulator casing so that the first step of unloading will be effected. As the pilot valve p is raised through successive steps uncovering the passages 19, 20 and 21 respectively in the regu-

lator and placing them in communication with atmosphere, the four main valves w will be actuated one after the other to effect the succeeding steps of unloading. When the pipe d is placed in communication with atmosphere, pressure behind the plunger X of the clearance valve Q is released and the valve opens until its plunger strikes the stop g . When the pipe j leading to the plunger casing of the stop g of the clearance valve P is open to atmosphere by the regulator, the stop is retracted by its spring and the clearance valve P moves to open the clearance chamber K to the cylinder for the third step of unloading. The final step is effected when the pipe k controlling the stop for the clearance valve Q is open to atmosphere. The machine is automatically loaded step by step as the valves operate in reverse order. Obviously this regulator may be operated by hand instead of automatically.

I claim:

1. In a compressor unloader, the combination of a cylinder and piston, inlet and discharge valves for the cylinder, a plurality of clearance chambers, and a single clearance valve controlling said plurality of chambers.

2. In a compressor unloader, the combination of a cylinder and piston, inlet and discharge valves for the cylinder, a plurality of clearance chambers, and a single clearance valve successively controlling said plurality of chambers.

3. In a compressor unloader, the combination of a cylinder and piston, inlet and discharge valves for the cylinder, a plurality of clearance chambers, and a single pressure fluid automatically actuated clearance valve for successively controlling said plurality of clearance chambers for step by step unloading.

4. In a compressor unloader, the combination of a cylinder and piston, inlet and discharge valves for the cylinder, a plurality of sets of clearance chambers, a single clearance valve for controlling each set of clearance chambers, and automatic pressure responsive means for actuating said clearance valves for step by step unloading.

5. In a compressor unloader, the combination of a cylinder and piston, inlet and discharge valves for the cylinder, a plurality of clearance chambers, a single clearance valve controlling said plurality of chambers, and a pressure fluid actuated stop for limiting the movement of said clearance valve.

6. In a compressor unloader, the combination of a cylinder and piston, inlet and discharge valves for the cylinder, a plurality of clearance chambers, a single pressure fluid automatically actuated clearance valve for successively controlling said plurality of clearance chambers for step by step unloading, and a pressure fluid actuated stop for

limiting the movement of said clearance valve to control the said steps of unloading.

7. In a compressor unloader, the combination of a cylinder and piston, inlet and discharge valves for the cylinder, a plurality of clearance chambers, a single clearance valve and stop for said valve for control

ling said plurality of chambers, both the valve and the stop being automatically responsive to receiver pressure. ¹⁰

In testimony whereof I have signed this specification.

CHESTER W. METZGAR.
